UNITED STATES PATENT OFFICE.

MADISON D. SHIPMAN, OF DE KALB, ILLINOIS.

DESIGN FOR A STUD MEMBER FOR GLOVE-FASTENERS.

SPECIFICATION forming part of Design No. 31,503, dated September 12, 1899.

Application filed June 29, 1899. Serial No. 722,239. Term of patent 14 years.

To all whom it may concern:

Be it known that I, MADISON D. SHIPMAN, a citizen of the United States, residing at De Kalb, in the State of Illinois, have invented and produced a new and original Design for the Stud Member of a Glove-Fastener; and I do hereby declare the following to be a full, clear, and exact description of the invention, such as will enable others skilled in the art to which it appertains to make and use the same.

The design pertains to surface ornamentation of the stud members of separable buttons or fasteners, such as are used upon gloves and other articles; and its essential features reside in a series of correspondingly-curved scrolls or spirals radiating from the base of a centrally-disposed bulb-form stud or projection over the top surface of the base-flange and from which said stud rises.

In the drawings which form a part of this specification, Figure 1 represents a top or plan view of the stud member of a separable fastener embodying my design; and Fig. 2 illustrates the same in cross-section, the section being taken on the line $x-x$ of Fig. 1.

Referring to the drawings by letters of reference, A denotes the base-flange, and C the bulb-form stud or projection rising therefrom.

B denotes a series of grooves, indentations, or depressions formed in or upon the surface

of the base-flange, which grooves or depressions radiate from the base of the stud or projection C in the form of scrolls or spirals and terminate in substantially circular enlargements b. Between the spirals or scrolls, near the periphery of the base-flange, indentations or depressions D may be formed to produce the appearance of a series of dots encircling the peripheral portion of said base, as shown.

The series of scrolls or spirals, as well as the dots between the same, may be produced in any proper manner, as by curves, indentations, or depressions formed in or upon the top surface of the base-flange.

It is apparent that this design is also applicable to snap-fasteners or buttons adapted to be used for various purposes and to jewelry and other articles.

Having thus fully described my invention, what I claim as new, and desire to secure by Letters Patent of the United States, is—

The design for a stud member of a glove-fastener, substantially as herein shown and described.

In testimony whereof I affix my signature in presence of two witnesses.

MADISON D. SHIPMAN.
